(57) **CLAIM**

The ornamental design for a wheel weight, as shown and described.

DESCRIPTION

FIG. 1 is a front, left and top perspective view of first embodiment of a wheel weight, showing my new design; FIG. 2 is a rear, right and bottom perspective view thereof; FIG. 3 is a front view thereof;

FIG. 4 is a rear view thereof;

FIG. 5 is an enlarged left side view thereof;

FIG. 6 is an enlarged right side view thereof;

FIG. 7 is a top plan view thereof;

FIG. 8 is a bottom plan view thereof;

FIG. 9 is a front, left and top perspective view of second embodiment of a wheel weight, showing our new design; FIG. 10 is a rear, right and bottom perspective view thereof;

FIG. 11 is a front view thereof;

FIG. 12 is a rear view thereof;

FIG. 13 is an enlarged left side view thereof;

FIG. 14 is an enlarged right side view thereof;

FIG. 15 is a top plan view thereof;

FIG. 16 is a bottom plan view thereof;

FIG. 17 is a front, left and top perspective view of third embodiment of a wheel weight, showing our new design; FIG. 18 is a rear, right and bottom perspective view thereof;

FIG. 19 is a front view thereof;

FIG. 20 is a rear view thereof;

FIG. 21 is an enlarged left side view thereof;

FIG. 22 is an enlarged right side view thereof;

FIG. 23 is a top plan view thereof;

FIG. 24 is a bottom plan view thereof;

FIG. 25 is a front, left and top perspective view of fourth embodiment of a wheel weight, showing our new design; FIG. 26 is a rear, right and bottom perspective view thereof;

FIG. 27 is a front view thereof;

FIG. 28 is a rear view thereof;

FIG. 29 is an enlarged left side view thereof;

FIG. 30 is an enlarged right side view thereof;

FIG. 31 is a top plan view thereof;

(Continued)

FIG. 32 is a bottom plan view thereof;
 FIG. 33 is a front, left and top perspective view of fifth embodiment of a wheel weight, showing our new design;
 FIG. 34 is a rear, right and bottom perspective view thereof;
 FIG. 35 is a front view thereof;
 FIG. 36 is a rear view thereof;
 FIG. 37 is an enlarged left side view thereof;
 FIG. 38 is an enlarged right side view thereof;
 FIG. 39 is a top plan view thereof;
 FIG. 40 is a bottom plan view thereof;
 FIG. 41 is a front, left and top perspective view of sixth embodiment of a wheel weight, showing our new design;
 FIG. 42 is a rear, right and bottom perspective view thereof;
 FIG. 43 is a front view thereof;
 FIG. 44 is a rear view thereof;
 FIG. 45 is an enlarged left side view thereof;
 FIG. 46 is an enlarged right side view thereof;
 FIG. 47 is a top plan view thereof;
 FIG. 48 is a bottom plan view thereof;
 FIG. 49 is a front, left and top perspective view of seventh embodiment of a wheel weight, showing our new design;
 FIG. 50 is a rear, right and bottom perspective view thereof;
 FIG. 51 is a front view thereof;
 FIG. 52 is a rear view thereof;
 FIG. 53 is an enlarged left side view thereof;
 FIG. 54 is an enlarged right side view thereof;
 FIG. 55 is a top plan view thereof;
 FIG. 56 is a bottom plan view thereof;
 FIG. 57 is a front, left and top perspective view of eighth embodiment of a wheel weight, showing our new design;
 FIG. 58 is a rear, right and bottom perspective view thereof;
 FIG. 59 is a front view thereof;
 FIG. 60 is a rear view thereof;
 FIG. 61 is an enlarged left side view thereof;
 FIG. 62 is an enlarged right side view thereof;
 FIG. 63 is a top plan view thereof; and,
 FIG. 64 is a bottom plan view thereof.

The broken lines shown in the drawings illustrate portions of the wheel weight that form no part of the claimed design.
